UNITED STATES PATENT OFFICE

ALBERT M. FREELAND, OF CHICAGO, ILLINOIS, ASSIGNOR TO CARL EDWARD, OF CHICAGO, ILLINOIS

PUMP OR ENGINE

Application filed September 27, 1928. Serial No. 308,784.

This invention relates to improvements in pumps or engines, particularly adapted, though not necessarily limited in its use as a compressor or in connection with pressure refrigerating systems and the like, and one of the objects of the invention is to provide an improved pump or engine of the reciprocating piston type, the pistons and cylinders being reciprocable one with respect to the other 5 and in which any desired number of co-operating piston and cylinder elements may be employed.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a vertical longitudinal sectional view of a pump or engine of this character constructed in accordance with the principles 25 of this invention.

Figure 2 is a transverse, vertical, sectional view taken on line 2—2, Figure 1, and looking in the direction of the arrows.

Figure 3 is a vertical, transverse, sectional view taken on line 3—3, Figure 1, looking in the direction of the arrows.

Referring more particularly to the drawing the numeral 10 designates a casing which may be of any desired size and configuration 35 and may be provided with an opening 11 having a removable closure 12 by means of which latter access may be had to the interior of the casing.

One end 13 of the casing preferably constitutes a valve plate having ports 14—15 therein, and which plate is held against rotation by means of suitable fastening screws 16.

Supported by the plate 13 is a hollow bearing 17 in which a shaft 18 is journaled, the bearing being preferably of an internal diam-

eter somewhat greater than the external diameter of the shaft. Arranged within the bearing 17 are ball bearings 19—20 in which the shaft is directly journaled. Encompassing the shaft 18 and within the bearing 17 is a spring 21, one end of which preferably rests against the bearing 20 and the other end against a washer 22, the washer in turn abutting a shoulder 23.

24 designates a removable closure in the end of the bearing 17 and beyond which closure one end of the shaft 18 projects. Secured to this projecting end of the shaft is a fan or blower 25 which co-operates with fins 26 on the valve plate 13 for cooling the structure.

The shaft 18 projects for a considerable distance into the casing 10 and secured to the shaft for rotation therewith and within the casing is a member 27 which is provided with cylinders 28, any number of which cylinders may be provided. In the present form of the invention three of such cylinders are provided and the cylinders are provided with cooling fins or ribs 29.

Reciprocable in each of the cylinders 28 is a piston 30 and the cylinders are ported, each cylinder being provided with a port 31, preferably in the bottom thereof, which successively communicate with the ports 14 and 15 in the valve plate 13.

At the other end of the casing 10 there is provided a bearing 32 which supports a stationary shaft 33. The axis of the shaft 33 is laterally displaced with respect to the axis of the shaft 18 and the shafts 33 and 18 are also spaced from each other in directions lengthwise of the shafts. One end 34 of the shaft 33 is disposed within the casing 10 and is deflected or bent laterally toward the shaft 18 so that the axis of the portion 34 will be inclined to the axes of the shafts 18—33.

Rotatably mounted upon the portion 34 of the shaft 33 is an element 35, ball bearings 36—37 being interposed between the element 35

35 and the shaft portion 34, the element 35 and the bearings 36—37 being secured in position by means of a suitable fastening nut 38.

Links 39 constituting piston rods, one for each of the pistons 30, are pivotally connected by one end as at 40 with the element 35 and at their other end as at 41 with the respective pistons 30. The connection 41 may be of any suitable construction but preferably the link 10 or piston rod 39 terminates in a ball shaped extremity secured within a bearing 42 carried by the piston 30.

With the structure thus formed and when the shaft 18 is rotated, which may be accomplished in any desired or suitable manner, 15 the member 27 will be rotated and with it the cylinders 28 and pistons 30. This rotation of the pistons 30 with respect to the portion 34 of the shaft 33 will cause the element 35 to 20 rotate upon its bearings and during the rotation of these parts there will be effected a reciprocatory movement of the pistons within the cylinders 28.

The air or fluid to be operated upon in the 25 cylinders 28, or to be compressed, is supplied to the cylinders through an inlet opening 43 in the valve plate 13 and has communication with the port 14 which is elongated and may be of any desired length according to the number of cylinders employed. As the cylinders 13 rotate the ports 31 there-in will successively communicate with the port 14 to receive the fluid to be operated upon. This will occur during the time that 35 the pistons are moving backwardly in the cylinders, creating a suction in the cylinders. At the time when the pistons 30 start to move forward on the compression stroke the ports 31 of the respective cylinders will 40 pass out of communication with the port 14 and the ports 31 will be closed by a flat portion 44 of the valve plate. Just before the completion of the movement of the piston in the compression direction or before the 45 piston 30 reaches the limit of its inward movement the ports 31 will pass into the communication with the port 15 in the valve plate 13, and with which latter port an outlet port 45 in the valve plate 13 has communication to convey the compressed charge to the desired point of use.

Thus it will be seen that there will be an alternate intake, compression and discharge in the successive cylinders.

55 The ports 31 in the cylinders are located, preferably at a considerable distance from the axes of rotation of the cylinders as are also the ports 14 and 15, and in order to hold the member 27 in contact with the valve plate 18 so as to maintain a tight joint between the two, the spring 21 is provided. The stress of the spring 21 tends to force the bearing 20 against a collar 26 carried by the shaft 18 and as the spring 21 also operates against the 60 shoulder 28, it will be manifest that the

spring will not only hold the parts firmly in contact, but will compensate any wear between the movable parts.

If for any reason it is desired to change the stroke of the pistons with respect to the end of the cylinder, the shaft 33 may be adjusted in a direction lengthwise of its axis. To that end this shaft is mounted loosely in the bearing 32, but is held against rotation by means of a suitable fastening device, such as a screw 47, the end of which enters a groove 48 in the shaft. Threaded into the bearing 32 is an adjustable member 49 which is held in its adjusted position by means of a lock nut 50. A screw 51 is provided with oppositely arranged threads 52—53. The threads 53 engage a threaded socket in the end of the shaft 33 and the threads 52 engage internal threads in the member 49. Thus, it will be seen that by adjusting the screw 51 the shaft 33 may be adjusted and when the proper adjustment has been obtained, the member 49 may be adjusted so as to engage the end of the shaft 33, after which the lock nut 50 may be adjusted.

If desired, an oil passage 54 may be provided, forming communication between the chamber 10 and the bearing 17, for lubrication.

While the preferred form of the invention 95 has been herein shown and described, it is to be understood that various changes may be made in the details of construction and in the combination and arrangement of the several parts, within the scope of the claims, 100 without departing from the spirit of this invention.

What is claimed as new is:—

1. In combination, a ported valve plate, a rotary member having cylinders arranged 105 to successively communicate with the ports of said plate, pistons in the cylinders, a rotatable element, piston rods pivotally connected with said element and the respective pistons, and means mounting said element for rotation about an axis inclined to the axis of rotation of said cylinders and laterally offset with respect to the axis of said rotary member, whereby the rotation of the cylinders will cause a reciprocatory movement of the pistons.

2. In combination, a ported valve plate, a rotary member having cylinders arranged to successively communicate with the ports of said plate, pistons in the cylinders, a rotatable element, piston rods pivotally connected with said element and the respective pistons, and means mounting said element for rotation about a stationary axis radially removed from and inclined to the axis of 120 rotation of said cylinders, whereby the rotation of the cylinders will cause a reciprocatory movement of the pistons.

3. In combination, a ported valve plate, a rotary member having cylinders arranged 125

- to successively communicate with the ports of said plate, pistons in the cylinders, a rotatable element, piston rods pivotally connected with said element and the respective pistons, means mounting said element for rotation about an axis inclined to and laterally spaced from the axis of rotation of said cylinders, whereby the rotation of the cylinders will cause a reciprocatory movement of the pistons, and means for adjusting said element in directions lengthwise of the axis of said rotary member and for maintaining said element in such adjusted position. 5
4. In combination, a ported valve plate, a rotary member having cylinders arranged to successively communicate with the ports of said plate, pistons in the cylinders, a rotatable element, piston rods pivotally connected with said element and the respective pistons, means mounting said element for rotation about an axis radially removed from and inclined to the axis of rotation of said cylinders, whereby a rotation of the cylinders will cause a reciprocating movement of the pistons in the cylinders, and means for adjusting said element in directions lengthwise of the axis of rotation of said cylinders and for maintaining the same in its adjusted position. 10
5. In combination, a ported valve plate, a rotary member having cylinders arranged to successively communicate with the ports of said plate, pistons in the cylinders, a rotatable element, piston rods pivotally connected with said element and the respective pistons, means mounting said element for rotation about a stationary axis inclined to and laterally spaced from the axis of rotation of said cylinders, whereby the rotation of the cylinders will cause a reciprocatory movement of the pistons, and means for holding the cylinders against the said valve plate and also operating to compensate wear therebetween. 15
6. In combination, a ported valve plate, a rotary member having cylinders arranged to successively communicate with the ports of said plate, pistons in the cylinders, a rotatable element, piston rods pivotally connected with said element and the respective pistons, means mounting said element for rotation about a stationary axis inclined to and laterally spaced from the axis of rotation of said cylinders, whereby the rotation of the cylinders will cause a reciprocatory movement of the pistons, and resilient means operating to hold the cylinders against the said valve plate and to also compensate wear therebetween. 20
7. In combination, a ported valve plate, a rotary member having cylinders arranged to successively communicate with the ports of said plate, pistons in the cylinders, a rotatable ball bearing element mounted for rotation on an axis inclined to the axis of rotation of said cylinders and laterally displaced with respect to the axis of rotation of the cylinders, piston rods connected with said element and the respective pistons, and means mounting said element for bodily adjustment in directions lengthwise of the longitudinal axis of the cylinders and for maintaining said element in its adjusted position. 25
8. In combination, a pair of fixed shafts laterally and longitudinally spaced from each other, a member supported by one of the shafts and having ported cylinders, a ported valve plate, means for rotating the last said shaft to cause a relative rotation of said cylinders and valve plate one with relation to the other stationary means for supporting the other of said shafts, the axis of the last said shaft being inclined to the axis of the first said shaft, an element rotatably mounted on the inclined portion of the second recited shaft, and piston rods connected with said element and the respective pistons whereby a relative rotation of the cylinders and valve plate will cause the said pistons to reciprocate in their respective cylinders. 30
9. In combination, a pair of fixed shafts laterally and longitudinally spaced from each other, a member supported by one of the shafts and having ported cylinders, a ported valve plate, means for rotating the last said shaft to cause a relative rotation of said cylinders and valve plate one with relation to the other, stationary means for supporting the other of said shafts, the axis of the last said shaft being inclined to the axis of the first said shaft, an element rotatably mounted on the inclined portion of the second recited shaft, piston rods connected with said element and the respective pistons whereby a relative rotation of the cylinders and valve plate will cause the said pistons to reciprocate in their respective cylinders, and means for bodily adjusting said element in directions lengthwise of the longitudinal axis of said cylinders and for maintaining said element in its adjusted position. 35
10. In combination, a rotatable shaft, a ported valve plate, a member having ported cylinders adapted to co-operate with the valve plate, means connecting one of the said parts with the shaft whereby the rotation of the shaft will cause a relative rotation of said plate and member, pistons in the cylinders, a stationary shaft spaced from the first said shaft both laterally and longitudinally, means supporting said stationary shaft for adjustment lengthwise of the axis thereof, a portion of the stationary shaft being inclined with respect to the first said shaft, an element rotatably supported by said inclined portion, and links pivotally connected with said element and the respective pistons. 40
11. In combination, a rotary member having ported cylinders, a ported valve member co-operating therewith, a rotary shaft to which one of said members is connected, pistons in the cylinders, a stationary shaft laterally spaced from the first said shaft, a sup- 45

port for the stationary shaft, a portion of said stationary shaft being inclined with respect to both of the shafts, an element rotatably mounted on said inclined portion, piston rods connecting said element with the respective pistons whereby rotation of the first said shaft will cause the pistons to reciprocate in the cylinders, an adjusting element for adjusting the stationary shaft in directions lengthwise of its axis and with respect to its support, and locking means for the adjusting element.

In testimony whereof I have signed my name to this specification, on this 19th day of September, A. D. 1928.

ALBERT M. FREELAND.
